Primary Examiner—Louis S. Zarfas*Attorney, Agent, or Firm*—Sterne, Kessler, Goldstein & Fox[57] **CLAIM**

The ornamental design for a shoe upper, as shown and described.

DESCRIPTION

FIG. 1 is left side elevational view of a shoe upper showing our new design;

FIG. 2 is a right side elevational view thereof;

FIG. 3 is a top plan view thereof;

FIG. 4 is a front elevational view thereof; and,

FIG. 5 is a rear elevational view thereof.

FIG. 1

FIG. 2

FIG. 3

FIG.4

FIG.5

UNITED STATES PATENT AND TRADEMARK OFFICE
CERTIFICATE OF CORRECTION

PATENT NO. : Des. 351,939

DATED : November 1, 1994

INVENTOR(S) : Susan B. Ryder

It is certified that error appears in the above-identified patent and that said Letters Patent is hereby corrected as shown below:

Title Page, Column 2, after "Fig. 5 is a rear elevational view thereof." please insert the following:

—The broken line showing of a shoe sole in the figures is environmental only and forms no part of the claimed design.—

Signed and Sealed this

Seventeenth Day of January, 1995

Attest:

BRUCE LEHMAN

Attesting Officer
